PROTECTIVE ORTHOPEDIC GARMENT

Julia E. Silverman, New York, N. Y.

Application November 1, 1951, Serial No. 254,357

6 Claims. (Cl. 128—287)

1

This invention relates to new and useful improvements in protective orthopedic garments.

It is common practice for persons victimized by poliomyelitis and similar diseases which render the legs unstable to wear braces on one or both legs for purposes of stiffening the legs to permit walking with or without the use of canes, crutches and similar hand held walking aids. Persons wearing such braces experience great difficulty in donning conventional panties, shorts and similar garments having leg openings through which the brace reinforced legs must be passed. It is the primary purpose of the present invention to construct such garments having leg openings so that they can be put on and taken off without having to pass them over the ends of the brace reinforced legs.

More specifically, the present invention proposes constructing garments of the type referred to especially for use by orthopedic persons characterized by a wrap-around body member having a vertically extended front opening arranged to be closed by suitable fastener elements in a manner so that the body member can be wrapped around the body at the bottom of the trunk over the top ends of the conventional braces and then secured in position using the fastener elements to close the front opening.

Another object of the present invention proposes providing the rear of the wrap-around body member with a depending crotch section arranged in a manner to be extended forward between the legs after the body member has been mounted in position on the body.

Still further, the present invention proposes constructing the edge portions of the body member on opposite sides of the front opening to be spaced from each other, in the closed position of the front opening, over at least the lower portion of their vertical height and to provide the crotch section with a front panel conformed to the shape of the space formed by the spaced lower portions of the edge portions of the body member and arranged in continuation of the crotch piece in a manner to be extended upward to occupy the space after the crotch section has been extended forward between the legs.

As a further object, the present invention proposes the provision of means for releasably securing the front panel to the material of the body member on opposite sides of the space to close the space and retain the crotch member in position between the legs.

The present invention proposes forming at least the bottom portion of the wrap-around

body member of waterproof material, in cases where the garment is constructed to be worn as an undergarment, so as to protect the outer garments from involuntary discharges in those cases where the disease which has disabled normal use of the legs has also destroyed the normal functioning of the bladder.

Still further, the present invention proposes constructing the undergarments so that they elastically close themselves about the legs and waist so as to completely confine the involuntary discharges within the garment.

A further object of the present invention proposes mounting tabs within the wrap-around body member at the front and rear thereof in a manner to have a catamenial or similar absorbent pad which is extended beneath the crotch and connected at its ends to the tabs so as to absorb the involuntary discharges or menstrual discharges.

As a still further object of the present invention, it is proposed to construct garments of the type disclosed embodying the basic wrap-around feature for use by orthopedic persons either as outer garments or undergarments.

It is a further object of the present invention to construct protective orthopedic garments of the type disclosed which are simple and durable, which are effective for their intended purposes and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

On the accompanying drawings forming a material part of the present disclosure:

Fig. 1 is a front elevational view of the protective orthopedic garment constructed in accordance with the present invention.

Fig. 2 is a rear elevational view of Fig. 1.

Fig. 3 is an enlarged detailed view similar to a portion of Fig. 1 showing a preliminary step in the process of opening the garment.

Fig. 4 is a view similar to Fig. 3 showing a further step in the process of opening the garment.

Fig. 5 is an inside elevational view of the garment as it appears when completely opened up.

Fig. 6 is an enlarged partial vertical sectional view taken on the line 6—6 of Fig. 5.

Fig. 7 is an enlarged partial vertical sectional view taken on the line 7—7 of Fig. 5.

The protective orthopedic garment, in ac-

2

cordance with the first form of the present invention shown in Figs. 1 to 7, includes a wrap-around body member 40 having a front opening. The garment is intended primarily for use by orthopedic persons wearing braces or the like to reinforce legs weakened by poliomyelitis or similar diseases. The wrap-around formation of the body member 40 permits the garment, which is constructed as a pair of panties to be worn under outer garments, to be put on and taken off without having to pass the garment over the bottoms of the legs.

The wrap-around body member 40 is of two-part construction consisting of an outer layer 41 and an inner layer 42 of waterproof material. The outer layer 41 is made of elastic material and has a back section 41^a and a pair of adjacent front sections 41^b. At the sides of the garment, the vertical side edges of the back section 41^a are joined to the vertical side edges of the front sections 41^b by vertically extended seams 43. To shape the top of the outer layer 41 to fit snugly about the waist of the wearer, gores 44 are extended downward from the top edges of the sections 41^a and 41^b. To give the bottom portion of the back section 41^a of the outer layer 41 a bucket-like formation to fit snugly beneath the rump of the wearer, gores 45 are extended in from the vertical side edges of the back section and gores 46 are extended upward from the bottom edge of the back section, see Fig. 2.

The elastic material used for forming the outer layer 41 is preferably one-way stretch elastic material arranged so that the outer layer will stretch in the girth only to have a compressing effect on the abdomen, hips and rump of the wearer.

The inner layer 42, as in the case of the outer layer 41, is formed to have a back section 42^a and a pair of adjacent front sections 42^b, co-extensive with the corresponding sections of the outer layer. The vertical side edges of the back section 42^a of the inner layer 42 are secured to the vertical side edges of the front sections 42^b by seams 47. From Fig. 5 it will be noted that the seams 47 of the inner layer 42 are in substantial alignment with the seams 43 of the outer layer 41.

The waterproof material used for forming the inner layer 42 is preferably a rubberized cloth although good results can be had using oiled silk or other similar waterproof materials.

The inner layer 42 is of a vertical height less than the vertical height of the outer layer 41. As best shown in Figs. 5 and 6, the top edge of the inner layer 42 is spaced some distance below the top edge of the outer layer 41. The top edge portion of the inner layer 42, see Fig. 6, is turned downward and outward between itself and the inner side of the outer layer 41 and there secured to the outer layer by a single line of elastic stitches 48. The outer layer 41 is stretched during stitching of the inner layer 42 thereto, so that the non-elastic nature of the inner layer 42 will not interfere with stretching of the elastic outer layer 41.

The top edge portion of the outer layer 41 is turned downward and inward and secured in position by a single line of stitches 49, see particularly Fig. 6. Stitching of the top edge portion of the outer layer 41 forms the top edge of the outer layer into a double layer elastic waistband 50 for snugly encircling the waist of the

wearer to completely isolate the interior of the garment when it is worn.

The front opening of the garment is characterized by the fact that the vertical side edges thereof are spaced from each other over at least the lower portion of their vertical height. In the present garment, the vertical side edges of the outer layer 41, on opposite sides of the front opening, are in abutment with one another. 10 The vertical side edge of one of the front sections 41^b has hooks 51 mounted thereon for engagement with complementary loops 52 mounted along the vertical side edge of the other of the front sections 41^b of the outer layer 41. When the hooks 51 and loops 52 are engaged, as shown in Fig. 1, the outer layer 41 is closed about the body.

The vertical side edges of the inner layer 42 merely abut one another at their top ends and have their lower portions diverged downward and outward, as best shown in Fig. 4, forming the space at the lower portion of the front opening.

The back section 42^a of the inner layer 42 continues at its bottom edge into an integral crotch section 53. The crotch piece 53 is provided for extension forwardly between the legs of the wearer of the garment. The crotch section 53 in turn continues into a front panel 54. The front panel 54 is triangular in shape conforming to the shape of the space formed by the diverging side edges of the front sections 42^b of the inner layer 42. After the crotch piece 53 has been extended forward between the legs, the front panel 54 can be extended upward between the diverging side edges of the front sections 42^b, closing the space.

Means is provided for releasably securing the diverging side edges of the front panel 54 to the diverging side edges of the front sections 42^b. The securing means comprises spaced post-type fastener elements 55 mounted along the side edges of the front panel 54. The fastener elements 55 are releasably engageable with complementary socket-type fastener elements 56 mounted along the side edges of the front sections 42^b. The position of the front panel 54 when the fastener elements 55 and 56 are engaged is shown in Figs. 1 and 3.

The bottom edges of the back section 42^a, the crotch piece 53 and the front sections 42^b, between the lower ends of the diverging side edges of the front sections 42^b and the diverging side edges of the front panel 54, are bounded by elastic tapes 57 secured in position by lines of stitches 58. Those bottom edges define leg openings, and the elastic tapes 57 are provided for engaging about the legs of the wearer to close the leg openings tightly about the legs to assist in the isolation of the interior of the garment when worn.

Secured to the vertical side edge of the one front section 41^b of the outer layer 41, there is a pad 59. The pad 59 is vertically elongated and secured along one edge to the respective front section 41^b by a vertically extended line of stitches 60. The pad 59 is provided to locate itself 65 behind the hooks 51 and loops 52, when engaged, to prevent those hooks and loops from digging into the flesh of the abdomen.

A pair of elastic tapes 61 are stitched to the lower end of the pad 59 and a fabric anchor tab 62 is in turn stitched to the lower ends of the tapes 61. Secured to the inside of the garment, at the rear thereof opposite the pad 59, there is an anchor piece 63. The anchor piece 63 is secured by stitches 64 to the inner face of the back

section 41^a of the outer layer 41 immediately above the top edge of the back section 42^a of the inner layer 42, see Fig. 5. Elastic tapes 65 depend from the bottom end of the anchor piece 63 and in turn have an anchor tab 66 secured to their bottom ends. The anchor tabs 62 and 66 are provided for having a pad of soft absorbent material, not shown connected thereto for absorbing any involuntary discharges of the wearer of the garment. In the event of an involuntary discharge, it is appreciated that the waterproof formation of the inner layer 42 of the garment will confine the moisture and prevent the outer garments from being soiled. The pad supported between the anchor tabs 62 and 66 could be the conventional catamenial pad to absorb the moisture of involuntary discharges or menstrual discharges.

From the foregoing description, it is apparent that the present invention provides a novel garment which can be completely opened up to be easily put on and taken off by orthopedic persons without having to pass the garment over the ends of the legs. At the same time, the garment is of part elastic construction to have a confining and compressing effect on the abdomen, hips and rump of the wearer completely eliminating the need for a separate foundation garment, and the garment has a waterproof lower portion to protect outer garments from soiling which results from involuntary or menstrual discharges.

From Fig. 1, it will be noted that the bottom edges of the front sections 41^b of the outer layer 41 are flatly converged downwardly and outwardly and that those bottom edges, adjacent the outer sides of the front section 41^b, overlap the elastic tapes 57 which bound the leg openings of the garment. Those bottom edges of the front sections 41^b where they overlap the elastic tapes 57 are secured thereto by lines of stitches 67, see particularly Fig. 7.

The present invention is characterized by the fact that the orthopedic garment can be completely opened up to be easily and quickly put on and taken off over the usual braces worn by such persons without having to pass the garment over the ends of the legs.

While I have illustrated and described the preferred embodiment of my invention, it is to be understood that I do not limit myself to the precise construction herein disclosed and the right is reserved to all changes and modifications coming within the scope of the invention as set forth in the appended claims.

Having thus described my invention, what I claim as new and desire to secure by United States Letters Patent is:

1. A protective orthopedic garment comprising a wrap-around body member having a vertically extended front opening, said member having adjacent vertical side edge portions on opposite sides of said front opening spaced from each other at least over the lower portion of their vertical height, means releasably joining said edge portions together above said spaced lower portions, a crotch section extended from the bottom of said body member at the rear thereof, a front panel continuing from said crotch section and conformed to the shape of the space formed by the spaced lower portions of said vertical edge portions, and means joining said front panel to the spaced lower ends of said vertical side edges, said wrap-around body member being formed of an outer elastic layer and an inner waterproof layer, said outer layer having its bottom portion

overlapping the top portion of said inner layer, and stitches securing the top edge of said inner layer to said outer layer.

2. A protective orthopedic garment comprising a wrap-around body member having a vertically extended front opening, said member having adjacent vertical side edge portions on opposite sides of said front opening spaced from each other at least over the lower portion of their vertical height, means releasably joining said edge portions together above said spaced lower portions, a crotch section extended from the bottom of said body member at the rear thereof, a front panel continuing from said crotch section and conformed to the shape of the space formed by the spaced lower portions of said vertical edge portions, and means joining said front panel to the spaced lower ends of said vertical side edges, said wrap-around body member being formed of an outer elastic layer and an inner waterproof layer, said outer layer having its bottom portion overlapping the top portion of said inner layer, and stitches securing the top edge of said inner layer to said outer layer, said first joining means comprising complementary hooks and eyes on the adjacent ends of said outer layer.

3. A protective orthopedic garment comprising a wrap-around body member having a vertically extended front opening, said member having adjacent vertical side edge portions on opposite sides of said front opening spaced from each other at least over the lower portion of their vertical height, means releasably joining said edge portions together above said spaced lower portions, a crotch section extended from the bottom of said body member at the rear thereof, a front panel continuing from said crotch section and conformed to the shape of the space formed by the spaced lower portions of said vertical edge portions, and means joining said front panel to the spaced lower ends of said vertical side edges, said wrap-around body member being formed of an outer elastic layer and an inner waterproof layer, said outer layer having its bottom portion overlapping the top portion of said inner layer, and stitches securing the top edge of said inner layer to said outer layer, said first joining means comprising complementary hooks and eyes on the adjacent ends of said outer layer, said inner layer having outwardly diverged side edges forming said space, said latter joining means comprising complementary snap fastener elements on said front panel and said diverged side edges of said inner layer.

4. A protective orthopedic garment comprising a wrap-around body member having a vertically extended front opening, said member having adjacent vertical side edge portions on opposite sides of said front opening spaced from each other at least over the lower portion of their vertical height, means releasably joining said edge portions together above said spaced lower portions, a crotch section extended from the bottom of said body member at the rear thereof, a front panel continuing from said crotch section and conformed to the shape of the space formed by the spaced lower portions of said vertical edge portions, and means joining said front panel to the spaced lower ends of said vertical side edges, said wrap-around body member being formed of an outer elastic layer and an inner waterproof layer, said outer layer having its bottom portion overlapping the top portion of said inner layer, and stitches securing the top edge of said inner layer to said outer layer, said first joining means

comprising complementary hooks and eyes on the adjacent ends of said outer layer, said inner layer having outwardly diverged side edges forming said space, said latter joining means comprising complementary snap fastener elements on said front panel and said diverged side edges of said inner layer, and elastic tapes binding the edges of said wrap-around body member, said crotch piece and the bottom of said front panel forming resilient leg openings.

5. A protective orthopedic garment comprising a wrap-around body member having a vertically extended front opening, said member having adjacent vertical side edge portions on opposite sides of said front opening spaced from each other at least over the lower portion of their vertical height, means releasably joining said edge portions together above said spaced lower portions, a crotch section extended from the bottom of said body member at the rear thereof, a front panel continuing from said crotch section and conformed to the shape of the space formed by the spaced lower portions of said vertical edge portions, and means joining said front panel to the spaced lower ends of said vertical side edges, 25 said wrap-around body member being formed of an outer elastic layer and an inner waterproof layer, said outer layer having its bottom portion overlapping the top portion of said inner layer, and stitches securing the top edge of said inner layer to said outer layer, said first joining means comprising complementary hooks and eyes on the adjacent ends of said outer layer, said inner layer having outwardly diverged side edges forming said space, said latter joining means comprising complementary snap fastener elements on said front panel and said diverged side edges of said inner layer, said outer elastic layer having its bottom edge stopped short of the bottom of said inner layer and turned inward and stitched in position.

6. A protective orthopedic garment comprising a wrap-around body member having a vertically extended front opening, said member having adjacent vertical side edge portions on opposite sides of said front opening spaced from each other at least over the lower portion of their vertical height, means releasably joining said edge portions together above said spaced lower portions, a crotch section extended from the bottom of said body member at the rear thereof, a front panel continuing from said crotch section and conformed to the shape of the space formed by the spaced lower portions of said vertical edge portions, and means joining said front panel to the spaced lower ends of said vertical side edges, said wrap-around body member being formed of an outer elastic layer and an inner waterproof layer, said outer layer having its bottom portion overlapping the top portion of said inner layer, and stitches securing the top edge of said inner layer to said outer layer, said first joining means comprising complementary hooks and eyes on the adjacent ends of said outer layer, said inner layer having outwardly diverged side edges forming said space, said latter joining means comprising complementary snap fastener elements on said front panel and said diverged side edges of said inner layer, said outer elastic layer having its bottom edge stopped short of the bottom of said inner layer and turned inward and stitched in position.
